UNITED STATES PATENT OFFICE.

MARY MATILDA CHEESEMAN, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,125, dated July 8, 1884.

Application filed May 23, 1884. Term of patent 31 years.

To all whom it may concern:

Be it known that I, MARY MATILDA CHEESEMAN, of the city, county, and State of New York, have invented and produced a new and original Design for a Pattern of a Lady's Costume, (numbered 9,260;) and I do hereby declare that the engraved prints accompanying this specification convey to any one accustomed to using paper patterns a clear understanding of how a garment made up by the pattern will appear.

The design shows a round walking-skirt and an over-dress. The over-dress exhibits closely-fitted basque-fronts outlining a point at the center, with depending side-plaited draperies extending nearly to the lower edge of the skirt

and flaring from the bottom of the basque closing; a closely-fitted back, extending the same depth upon the skirt, and displaying under folded plaits at the ends of its body-seams; a standing collar, and coat-sleeves showing gathers and a high roll at the shoulders.

What I claim as my invention, and desire to secure by Letters Patent, is--

The design for a lady's costume, as shown in the engraved prints accompanying this specification.

MARY MATILDA CHEESEMAN.
